DETECTOR DEVICE SUITABLE FOR USE WITH CIGARETTE-MAKING MACHINES

Gordon Francis Wellington Powell and Richard Graham Crosland, both of Deptford, London, England, assignors to Molins Machine Company, Limited, London, England, a British company

Application January 20, 1958, Serial No. 710,000

Claims priority, application Great Britain
January 25, 1957

5 Claims. (Cl. 131—21)

This invention concerns a detector device suitable for use with cigarette-making machines, said machines being of the kind in which stubs and pieces of cigarette rod are assembled for joining to form a composite rod by feeding them axially in alignment as a step in the manufacture of mouthpiece cigarettes.

In some cigarette-making machines of the kind referred to the pieces of cigarette rod are cut from a continuous rod, while in other machines the pieces are fed from a hopper.

In the first type of machine failure of the mechanism may occur from breakout of the cigarette rod, that is, the continuous rod is imperfectly sealed; failure of the stub supply; or transfer blockage, that is, the mechanism to which the assembled pieces are transferred for further treatment becomes jammed for some reason.

In the second type of machine failure may occur due to failure of the supply of pieces of cigarette rod; failure of the stub supply; or transfer blockage.

It will be readily understood by those skilled in the art that (depending on the type of machine) if one of the components fails to arrive at the position where they are grouped ready for joining, the resulting rod will be defective or it may be that a rod cannot be formed because a component is missing or a piece of cigarette rod is defective. Loose pieces of material can easily upset the operation of mechanism to which the group is passed and defective cigarettes must not pass unnoticed to the delivery end of the machine so it is imperative that the machine shall stop to enable the operator to clear the fault and determine the cause of the fault, if it is not immediately obvious.

The present invention provides a photo-electric detector suitable for this purpose.

The devices herein specifically described are adapted for use in a machine of the first type and, moreover, one in which two pieces of rod with a double length stub between are joined to produce a short composite rod which is thereafter bisected to produce two mouthpiece cigarettes but as will be seen the invention is generally applicable to detection of faults occurring in any succession of workpieces moving in spaced relationship, that is, if the pieces do not continue to move at the proper rate and are not properly spaced the detector device will operate to stop the machine.

According to the invention there is provided a device for detecting spacing and motion faults in a succession of workpieces moving in spaced relationship, comprising a photo-electric detector, the cell whereof is illuminated as the trailing end of a workpiece passes out of the light beam directed on to said cell and a further photo-electric detector the cell whereof is obscured as the leading end of the succeeding workpiece passes into the light beam directed on to the cell of said further detector, the first said detector being adapted, as its cell becomes illuminated, to cause the energisation of a

2

relay and the second said detector being adapted to prevent energisation of the relay by the first said detector unless the cell of the second said detector is obscured. Thus if the spacing between two succeeding workpieces

5 is not correct or one workpiece is not moving in correct timed relationship with the other, for example, one has ceased to move, the relay condition is affected and this abnormal condition may be used to give a signal or stop the movement of the machine in which said workpieces move.

Further according to the invention there is provided a device for use on a cigarette-making machine of the kind wherein short composite rods comprising two pieces of cigarette rod with an intervening double-length stub 15 are assembled for the purpose of manufacturing mouthpiece cigarettes, said device comprising a photo-electric detector the cell whereof is illuminated as the trailing end of a composite rod group passes out of the light beam directed on to said cell and a further photo-electric detector, the cell whereof is obscured as the leading end of the succeeding composite rod group passes into the light beam directed on to the cell of said further detector, the first said detector being adapted as its cell becomes illuminated to cause energisation of a relay and 20 the second said detector being adapted to prevent energisation of the relay by the first said detector unless the cell of the second said detector is obscured, the relay having contacts which close when the relay is energised and which are in a control circuit for a motor driving 25 said machine and open to stop the motor unless the relay is energised by the first said detector. Means may be provided for rendering the device inoperative while the machine is starting to run and for preventing the motor from being re-started after it has been stopped 30 by the detector until certain requirements have been fulfilled and the machine is in proper order. For amplification of the detector impulses and as a control device for the relay, transistors are used.

The invention further comprises a device as set forth 40 in the preceding paragraph comprising apparatus whereby a signal pulse originating by illumination of the cell of the first detector is fed to an amplifier through a diode biased to control conduction and the amplified signal is fed to the relay, and a coupling between the cell of the 45 first detector and the cell of the second detector whereby the output from the first cell is fed to the second cell which has a load resistance in series therewith, the lead to said diode being connected to the joint between cell and resistance whereby when the second said cell is 50 illuminated and its impedance falls the voltage applied to the diode is insufficient to overcome its standing bias and the signal pulse cannot pass the diode, while if the second said cell is not illuminated its impedance remains high and the voltage applied to the diode overcomes 55 the standing bias and the pulse passes to the amplifier to cause energisation of the relay and the closure of its contacts. The apparatus may further include a condenser which maintains the supply to the relay during the interval between the pulses (i.e. the time taken for a group to pass completely through the device) said 60 condenser discharging shortly after the expiration of said interval unless a further pulse occurs.

The invention will be more fully described with reference to the accompanying drawings in which:

65 Figure 1 is a front elevation of part of a cigarette-making machine in which two pieces of rod with a double length stub between are joined to produce a short composite rod, and showing the detecting apparatus in position.

70 Figure 2 is a side elevation of Figure 1.
Figures 3A, 3B and 3C show, in combination, the cir-

cuits and other electrical details of the apparatus, but the figures are drawn separately for the purpose of easier understanding.

Figures 4A, 4B and 4C are diagrams to illustrate the functioning of the apparatus under three different conditions.

In the apparatus about to be described, the function of the apparatus is to detect any of the following faults:

(a) Failure of cigarette supply which is normally due to breakout of cigarette rod.

(b) Failure of stub supply.

(c) Transfer blockage.

On the occurrence of any of these faults, the main driving motor of the machine is stopped.

Referring first to Figure 1, the detection apparatus consists of two photo-detecting heads, 1 and 2, each of which has a photo-cell which is illuminated by a beam of light projected from a lamp 3 and reflected by prisms 4 across the path of the cigarette components which consists of pieces of cigarette rod 5 and stubs 6. The photo cell of the head 2 can be seen in Figure 2 where it is marked 16.

The cigarette components have already been fed to a travelling tape 7 on which they have been aligned and abutted. In the present example the cigarettes have been cut from a continuous cigarette rod formed in the usual way on apparatus well to the right of Figure 1 and after rod-cutting the stubs have been fed into the intervening spaces from a stub hopper with suitable devices for feeding stubs on to the tape and other devices for causing the components to abut as shown.

It will however be understood that the components can be supplied to the tape in any other known way. Alignment is preserved on the tape by an overhead travelling endless band device consisting of a pair of helical springs 8, Figure 2.

The head 1 is the "detector" head, and produces a signal pulse each time the trailing end of the piece of cigarette rod (hereafter briefly termed "a cigarette") at the end of a group passes by it, thereby exposing the photo-cell of said head to the light beam. The other head 2 (referred to henceforth as the "gate" head) only allows the pulse from the detector head to be used under normal running conditions.

Referring now to Figures 3A, 3B and 3C, each detector pulse causes a relay 10, Figure 3C, to be energised and its contacts 11 to remain closed (as explained in more detail later) and as long as this condition exists the contacts 11 maintain the circuit to the starter of the motor which drives the machine but as will now be seen detector pulses are only permitted to energise the relay as long as the performance of the machine is correct.

On the occurrence of either of the faults *a* or *b* referred to above the gate head prevents the detector pulse from operating the relay, whose contacts 11 thus become disengaged, breaking the supply to the machine driving motor, and thereby stopping the machine.

When transfer blockage occurs there is no detector pulse available and so the relay 10 becomes disengaged and its contacts 11 open and the driving motor circuit is broken.

The description and operation of the apparatus shown in Figures 3A, 3B and 3C can be roughly divided into four sections, viz:

- (i) pulse generation circuit and gating.
- (ii) pulse shaper and amplifier.
- (iii) output.
- (iv) power supply.

The essential circuit of item (i) is shown in Figure 3A. The photo-electric cell 12 of the detector head 1 is of the cadmium selenide photo-conductive cell type. When the cell is darkened, it has a high impedance (several megohms) and little current flows through it. On exposure to light, the cell impedance falls to a few hundred ohms; the resultant current surge in the primary 13 of a transformer

14 produces a pulse to the gating network comprising a resistor 15, photo-electric cell 16 of the gate head and blocking diode (a germanium type diode) 17, suitably biased as explained later.

If the gate cell 16 is illuminated, this pulse (negative) is largely attenuated, by the relative impedances of resistor 15 which is fairly high and of the gate cell which is quite low. The bias applied to the blocking diode 17 is sufficient to prevent the pulse overcoming the high impedance of the diode, and it is blocked from the amplifier which is shown in Figure 3B.

If, however, the gate cell 16 is darkened, its impedance is much higher, (due to the inherent time constant of the type of cell it does not reach its final value of up to 5 megohms, in the time available; however, its impedance is at least several thousand ohms) and there is thus a sufficiently large pulse developed across the gate cell to raise the potential of the diode cathode negative, in respect to the diode anode; that is, to overcome the blocking bias on the diode, and take it into the conducting region. Current can thus flow through the diode 17 and along line 0 to the amplifier.

Figure 3B shows the essential components of the pulse shaper and amplifier. This amplifying circuit is, in effect, a mono-stable switch, producing a (nominally) square pulse output of constant amplitude and duration, on the application of the requisite triggering pulse. The circuit employs two transistors, 18 and 19. A resistor 9 connects the emitters of these transistors to the positive line. The current in this resistor develops a voltage at the transistor emitters which fixes the base to emitter bias.

Normally, the high negative bias applied to the base of the transistor 18 (p. n. p. junction transistor) by a resistor 20, is sufficient to cause base current to flow, of sufficient magnitude to saturate the collector; that is, to bring the collector volts down to the "bottomed" condition by the voltage drop across a resistor 21 caused by the large collector current. The voltage drop across resistors 22 and 23 results in the base of transistor 19 being held positive to the emitter, because of the current flowing in transistor 18 and in the common emitter resistor thereby cutting off the transistor 19.

This potential is also used to provide the negative blocking bias for the diode 17.

On application of the triggering pulse, a positive pulse appears on the collector of transistor 19 as it starts conducting, which pulse is applied to the base of transistor 18 through a capacitor 24 thereby taking the transistor 18 into the cut-off region. The collector current falls, resulting in an increase in volts across resistors 22 and 23, and eventually the unstable condition is reached whereby the base current of transistor 19 through resistor 22 is sufficient to saturate said transistor 19. Transistor 18 is held cut off by the charge in the capacitor 24. This charge is, however, leaking away exponentially through the resistor 20 and another marked 25 and after a time (depending upon the magnitude of the charge, and of the relative potentials of the emitter, and the supply volts, together with the values of resistor 20, capacitor 24, and resistor 25) the base of transistor 18 falls negative to its emitter, and the transistor starts conducting, the potential across resistors 22 and 23 falls making the base of transistor 19 positive to its emitter, thereby cutting off said transistor and the collector volts rise negative and apply a saturating negative pulse to the base of transistor 18 through capacitor 24.

The unit then remains in that condition until the arrival of a further pulse from the detector head. The output from the amplifier is taken from the collector of transistor 18 by the line marked 0'.

The output stage is shown at the left of Figure 3C. In order to provide a degree of integration of the output pulses, the output is fed from Figure 3B along the line 0' through a diode 26 (a germanium diode) to a reservoir condenser 27. This condenser charges rapidly through

resistor 21 when the transistor 18 is cut off, but retains its charge when transistor 18 switches on except insofar as it discharges through resistors 29 and 30 and the base of a transistor 31. Thus although as previously stated the relay coil is energised at each detector pulse and in other circumstances this would mean that the relay contacts would open at the end of a pulse they in fact remain closed because the stored charge in the condenser 27 causes the transistor 31 to feed the relay coil in the interval between the pulses. If a pulse does not occur then the condenser discharges and the motor control circuit is broken.

In the conducting region the input impedance of transistor 31 is a few hundred ohms, so that resistor 30 supplies negligible damping and only serves to provide a low impedance base-emitter circuit when capacitor 27 is discharged.

The base current flowing when capacitor 27 is charged is sufficient to saturate the transistor 31 thus applying the full D.C. volts across the relay 10. In the event of the non-arrival of a pulse at transistor 19 the charge on capacitor 27 rapidly decreases, reducing the collector current of transistor 31 and the relay 10 disengages thereby switching off the driving motor of the machine.

The power supply apparatus is shown at the right of Figure 3C. A transformer 32 has two secondary windings, one, 33 to feed the lamps 3 and the other, 34 in series therewith to provide a voltage which after bridge rectification by a normal selenium metal rectifier 35 smoothed by capacitors 36 gives approximately 18 volts D.C. supply, though this value is merely by way of example.

A supply for the detector cell is obtained from the 18v supply by a potential divider consisting of resistors 37 and 38 with a smoothing capacitor 39, see Figure 3A.

Referring again to Figure 1 it will be seen that the detectors are jointly adjustable along a bar 40 while they are separately adjustable on round rods 41.

The spacing between the trailing ends of two groups i.e. the distance X on Figure 1 is fixed at 209 mm. irre-

Further, it is common in cigarette-making machines to use a lever operated clutch in the main drive so that ordinarily the driving motor can be started and then the clutch is engaged to drive the machine. This arrangement is employed in the machine in question and therefore a further micro-switch (not shown) is fitted to the main starting lever mechanism and is arranged for connecting into the driving motor circuit so that after the photo-electric detector has stopped the driving motor, this motor cannot be restarted until the clutch has been disengaged.

In order to assist in the full understanding of the invention as at present applied, Figures 4A, 4B and 4C are provided and together with the table given below show what happens under various conditions likely to occur in practice.

Referring first to Figure 4A which shows normal running conditions, the fundamental principle is that the gate is "closed" when the light beam is falling on the cell, and "open" when the light beam is obscured by the cigarette rod. The signal pulse is produced by the exposure of the detector cell rod to the light beam as a cigarette passes from in front of it. Under normal conditions the next cigarette has, by this time, obscured the gate cell, thereby opening the gate, and allowing the pulse to be fed to the amplifier, to keep the relay energised.

In Figure 4B it is supposed that the stub supply has failed in respect of the right-hand group. Thus, the space between the trailing end of the last cigarette of the first group and the leading end of the first cigarette of the succeeding group is increased, and gate cell is not yet obscured, thereby closing the gate and preventing the pulse from being fed to the amplifier: the relay thus becomes disengaged.

In Figure 4C the supply of cigarettes has ceased, for example, there has been a break-out in the rod. Again the spacing has increased so the consequences are the same as for Figure 4B.

These results, with others due to faults likely to occur, are now shown in tabular form.

Conditions	Action on detectors and relay		
	Detector	Gate	Relay
(1) Normal operation	Produces pulse	Open	Energised.
(2) Stub failure	do	Closed	Desengages provided that 2 or more successive cigarettes are without plugs.
(3) Cigarette failure	The stubs produce pulse	do	Disengages.
(4) Transfer blockage	No pulse	do	Do.
Both cells continuously illuminated.	do	Open	Do.
Both cells continuously in darkness.	do	Open (but no pulse from detector).	Do.
(5) Other blockage conditions—Both cells obscured.	do		

spective of the length of the cigarettes and stubs. Then if Y is the distance between the inside faces of the prisms of the two detectors as indicated in Figures 4A, 4B and 4C:— $Y=209$ mm. minus (group length plus 5 mm.).

In the machine specifically described the three assembled components to make the short composite rod are passed to mechanism where a cork tip is rolled around them to join the stub piece to the neighbouring ends of the cigarettes. Also as previously remarked the stubs are fed from a hopper and the cigarettes are cut from a continuous rod. In starting such a machine it is first necessary to get a satisfactory continuous rod made and then start the stub feeding devices, and the cork-tip mechanism. Thus during the time before the stub feed is applied on starting up the machine, there would apparently be a fault (equal to failure in stub supply or the break-out condition) and the machine would be switched off. To counteract this, a micro-switch 42 is fitted which holds the relay 10 permanently energised, until such time as the cork feed mechanism is engaged, and the normal conditions of running exist.

It is to be noted that the detector only produces a pulse correctly when the trailing end of the end cigarette of a group is moving across it.

The gate is open when not illuminated and is closed when illuminated.

For certain purposes the gate and the gating network may be dispensed with in which case the detector pulse goes to the amplifier without hindrance each time it is produced. For example, if it is only a question of detecting a continuous succession of spaced cigarettes it is possible to operate in this manner, the apparatus shown in Figures 3A, 3B and 3C being very suitable for detecting purposes even without the gating device.

What we claim as our invention and desire to secure by Letters Patent is:

1. Apparatus for detecting spacing and motion faults in a succession of workpieces moving in spaced relationship, comprising a first photoelectric detector having a photoelectric cell and means for directing a beam of light thereon, said cell becoming illuminated as the trailing end of a workpiece passes out of the light beam directed

on to said cell, a second photoelectric detector having a photoelectric cell and means for directing a beam of light thereon, said last named cell being obscured as the leading end of the succeeding workpiece passes into the light beam directed on to the cell of said second detector, a relay, and a circuit connecting said cells and said relay for energizing said relay on illumination of the cell of said first detector unless the cell of said second detector is concurrently obscured.

2. Apparatus for use on a cigarette-making machine having an electric driving motor and a control circuit therefor, said machine being of the kind wherein short composite rods are assembled from composite rod groups comprising two pieces of cigarette rod with an intervening double length stub, for the purpose of manufacturing mouthpiece cigarettes, said apparatus comprising a first photoelectric detector having a photoelectric cell and means for directing a beam of light thereon, said cell becoming illuminated as the trailing end of a composite rod group passes out of the light beam directed on to said cell, a second photoelectric detector having a photoelectric cell and means for directing a beam of light thereon, said last named cell being obscured as the leading end of the succeeding composite rod group passes into the light beam directed on to the cell of said second detector, a relay, and connections between said cells and said relay for energizing said relay on illumination of the cell of said first detector unless the cell of said second detector is concurrently obscured, said relay having contacts which close when the relay is energized, which are

in said control circuit for the motor, and which are open to stop the motor unless the relay is energized by the said first detector.

3. Apparatus as claimed in claim 2 comprising a power supply adapted to energize the relays, and a switch which when closed connects the relay directly to said power supply to render the detecting device inoperative while the machine is starting to run.

4. Apparatus as claimed in claim 1 in which the circuit connecting said cells and said relay includes a blocking diode normally biased beyond cut-off, means operative on illumination of the cell of said first detector to deliver a pulse to said diode to render the latter conducting, the cell of said second detector being arranged in shunt with said diode so as to by-pass said pulse when said last mentioned cell is illuminated to reduce its impedance, and means including an amplifier delivering pulses from said diode to said relay.

5. Apparatus as claimed in claim 4 comprising a condenser which discharges to the relay to maintain it in the energized state during the interval between the pulses and a resistance connected to said condenser and through which it discharges shortly after the expiration of said interval unless a further pulse occurs.
